UNITED STATES PATENT OFFICE.

REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE.

PUMP.

Application filed March 14, 1921. Serial No. 452,302.

To all whom it may concern:

Be it known that I, REINHARD HILDEBRAND, a citizen of Germany, and a resident of Webster Groves, in the county of St. Louis and State of Missouri, have invented certain new and useful Improvements in Pumps, of which the following is a full, clear, and exact description, reference being had to the accompanying drawings, forming a part of this specification.

This invention relates to improvements in pumps, and more particularly to a pump adapted to be actuated by a reciprocating member such as the piston of an engine. A pump of this type may be used to force a fluid of any kind, for example oil, to the piston of an internal combustion engine.

The object of the invention is to produce a simple and highly efficient pump of this kind. More specifically stated, an object is to avoid the severe stresses which ordinarily result from a sudden or rapid movement of the movable element of the pump. In the preferred form of the invention, the pump is actuated through the medium of a striking member carried by the reciprocating piston of the engine and adapted to engage the movable pumping member in such a manner that the latter is suddenly actuated by the engine piston. The movable pumping member receives a hammer blow which is struck by the movable striking member, and as a result of the sudden and rapid motion, fluid in the pump is momentarily subjected to a very high pressure. To relieve this pressure, the pump is preferably provided with an open inlet permitting backward flow of some of the fluid in response to the pressure transmitted from the striking member.

A further object is to provide a simple automatic valve device whereby the fluid passageway of the pump is positively opened at the beginning of the discharge stroke of the pump. This valve device preferably includes a valve secured to one of the pumping members and adapted to engage a valve seat in the other pumping member, so that when the movable pumping member is in motion the valve will be positively separated from its seat. The valve preferably cooperates with its seat to form a stop device for limiting the movement of the movable pumping member, and if a spring is used to restore the movable pumping mem-

ber, this spring can also serve as means for closing the valve device. Furthermore, the valve may be adjusted, as will be hereafter described, to vary the starting position of the movable pumping member.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. 1 is a vertical section illustrating certain parts of an engine equipped with my pump, the latter being shown in elevation.

Fig. 2 is an enlarged vertical section illustrating the pump.

Fig. 3 is a vertical section, partly in elevation, showing the striking member whereby the pump is actuated.

The engine herein shown comprises a cylinder 1, a piston 2 adapted to reciprocate in the cylinder, a piston pin, or wrist pin, 3 mounted in the piston, a crank 4 located below the cylinder, and a connecting rod 5 whereby the piston pin 3 is connected to the crank pin 4'. These elements may form parts of an internal combustion engine, and they may be constructed in any suitable manner.

The pump herein disclosed is adapted to form part of the means for lubricating the engine, although it is to be understood that the invention is not limited to such use. The piston pin 3 is provided with an inlet passageway 6 communicating with a longitudinal passageway 7 which leads to a transverse passageway 8, the latter terminating at the periphery of the piston pin. After the pin has been drilled to form these passageways, the upper end of passageway 6 may be closed by a plug 9 and one end of passageway 7 may be closed by a plug 10. 11 designates an inlet port formed in the piston 2 and communicating with the inlet passageway 6 in the piston pin. A tube 12 is screwed into the port 11 and a striking member 13 is screwed onto the lower end of said tube. The striking member 13 is thus carried by the piston to which it is preferably secured by means of the tube 12 and also by means

of a holder 14 secured to the piston and surrounding the striking member 13. Before describing the details of the pump, I will state that the striking member 13 serves 5 as means for transmitting motion to the pump, and that the lubricating oil discharged from the pump passes through the striking member and also through the tube 12 to the passageways 6, 7 and 8 in the piston pin, whereby the oil is conducted to the periphery of said pin. The bottom of the striking member 13 (Fig. 3) is provided with an inlet port 15 which is normally closed by a check valve 16 having a non- 10 circular extension 17. 18 designates a spring tending to retain the check valve 16 in its closed position, said spring being interposed between the top of the valve extension 17 and the bottom of a spring seat 19, 15 the latter being formed by a washer having a central opening through which the oil is discharged from the striking member to the tube 12.

As an illustration of a pumping device 20 embodying the features of this invention, I have shown a movable pumping element A and a stationary pumping element B telescoping therewith. The movable pumping element comprises a tubular plunger 20 having a longitudinal passageway for the discharge of oil and also having a valve seat 21 in said passageway. A metal washer 22 is seated on the top of the plunger 20 and an abutment 23, preferably made of fiber, is seated 25 on the top of this washer. A ring 24 is screwed onto the upper end of plunger 20 and provided with an inturned flange 25 (Fig. 2) adapted to bear upon an outwardly extending flange on the abutment 23 so as to firmly secure the latter to the plunger 20. The ring 24 may be split transversely, as suggested at 24' in Fig. 2, and after this split ring has been tightened it may be locked through the medium of a clamping bolt 26 whereby the ring is contracted to grip the threaded upper end of the plunger 20. The washer 22 and abutment 23 are provided with central openings through which the oil is discharged from the pump. 30 The main function of the washer 22 is to provide a substantial bearing surface for the fiber abutment 23.

The stationary pumping element B comprises a tube, or cylinder, 27 in which the plunger 20 is slidably mounted, said tube 27 being screwed into a bracket 28 which is fixed to a stationary part of the engine. It will be noted that the screw threaded tube 20 may be adjusted longitudinally to vary the location of the pumping device. Near its lower end (Fig. 2), the tube 27 is provided with restricted inlet ports 29, and a bushing 30 is screwed into the lower end of this tube to receive a conductor 31 whereby 35 oil is transmitted to the pump. This con-

ductor preferably leads from a point higher than the pump, so that the oil can flow by gravity to the pump. A stationary check valve 32 (Fig. 2) engaging the valve seat 21, is provided with a long stem 33, adjustably secured in the tube 27, the lower end of said stem being screwed into the ported wall 34 near the lower end of tube 27. 30' designates a transverse pin (Fig. 2) whereby the valve stem 33 is secured after it has been properly adjusted in the ported wall 34. Guide ribs 35 may be formed on the valve stem 33 so as to engage the wall of the longitudinal passageway in the plunger 20. 36 designates a restoring spring whereby the plunger 20 is moved to its elevated position, shown by Fig. 2, said spring being interposed between and engaged with the plunger 20 and the ported wall 34.

The discharge passageway formed in the plunger 20 may be closed by the valve 32, but the inlet at the lower end of the pump is always open. The valve 32 is secured to a stationary part of the pump, but it cooperates with a valve seat on the movable plunger 20, and it serves as means for limiting the upward motion of the plunger. It is to be understood that the plunger 20 is moved upwardly through the medium of the restoring spring 36, and that this spring tends to retain the valve seat 21 in engagement with the stationary valve 32.

The operation of the device may be briefly described as follows:

During each downward stroke of the engine piston 2, the striking member 13 engages the abutment 23 at the top of the movable pumping element, thereby forcing the plunger 20 downwardly in the tube 27. At this time, the inlet port 15 (Fig. 3) in the bottom of the striking member 13, registers with the central opening in the abutment 23, and as the piston continues its downward motion, oil is forced from the pump and through the striking member 13 and tube 12 to the piston pin 3. During the upward stroke of the engine piston, the striking member 13 passes from the abutment 23, as suggested by Figs. 2 and 3, and the spring 36 restores the pump plunger 20 to the position shown by Fig. 2. The striking member 13 is carried by the engine piston and it moves very rapidly, with the result of striking severe hammer blows on the abutment 23, thereby transmitting sudden and rapid movements to the pump plunger 20. In response to these sudden movements, some of the oil is forced backwardly through the restricted inlet ports 29 at the lower end of the pumping device, said ports being constantly open to relieve the pressure resulting from the sudden motion of the pump plunger 20.

At the beginning of each downward stroke of the pump plunger 20, the oil

should be permitted to freely escape past the valve 32. It is therefore important to note that the plunger 20 carries the valve seat 21, and that this seat must move downwardly with the plunger so as to positively open the valve device at the beginning of the downward motion of the pump plunger.

I claim:

1. A pump comprising two pumping elements one of which is movable relative to the other so as to force fluid through the pump, and operating means comprising a striking member movable into and out of engagement with the movable pumping element, said striking member and movable pumping element having registering discharge passageways through which fluid is discharged while the striking member is engaged with the movable pumping element, and the other pumping element having an open inlet permitting reflux of some of the fluid in response to the pressure transmitted from said striking member.

2. A pump comprising two pumping elements one of which is movable relative to the other so as to force fluid through the pump, and operating means comprising a striking member movable into and out of engagement with the movable pumping element, said striking member and movable pumping element having registering discharge passageways through which fluid is discharged while the striking member is engaged with the movable pumping element, said movable pumping element being provided with a discharge valve adapted to close the discharge passageway therein, and the other pumping element having a constantly open inlet permitting reflux of some of the fluid in response to the pressure transmitted from said striking member.

3. A pump comprising two pumping elements one of which is movable relative to the other so as to force fluids through the pump, and operating means comprising a striking member movable into and out of engagement with the movable pumping element, said striking member and movable pumping element having registering discharge passageways through which fluid is discharged while the striking member is engaged with the movable pumping element, said striking member and movable pumping element being provided with check valves permitting the discharge of fluid through said passageways, and the other pumping element having a constantly open inlet permitting reflux of some of the fluid in response to the pressure transmitted from said striking member.

4. In a machine having a reciprocating piston, a pump comprising two pumping elements one of which is movable relative to the other so as to force fluid through the pump, a striking member carried by said

reciprocating piston and movable into and out of engagement with the movable pumping element, said striking member and movable pumping element having registering discharge passageways through which fluid is discharged while the striking member is engaged with the movable pumping element, and the other pumping element having a constantly open inlet permitting reflux of some of the fluid in response to the pressure transmitted from said striking member.

5. In a machine having a reciprocating piston, an oil pump comprising a stationary pumping element and a movable pumping element cooperating therewith to force the oil through the pump, a striking member carried by said reciprocating piston and movable into and out of engagement with said movable pumping element, said striking member and movable pumping element having registering oil passageways through which the oil is discharged to said reciprocating piston, and said stationary pumping element having an open inlet permitting reflux of some of the fluid in response to the pressure transmitted from said striking member.

6. In a machine having a reciprocating piston, a pump comprising a pumping element movable with said reciprocating piston, and a stationary pumping element cooperating with said movable pumping element to force fluid through the pump, said movable pumping element being provided with a discharge passageway leading to said piston, and said stationary pumping element having an open inlet permitting reflux of some of the fluid in response to the pressure transmitted from said reciprocating piston.

7. In a machine having a reciprocating piston, a pump comprising a pumping element movable with said reciprocating piston, and a stationary pumping element cooperating with said movable pumping element to force fluid through the pump, said movable pumping element being provided with a discharge passageway leading to said piston and a check valve preventing reflux of fluid in said discharge passageway, said stationary pumping element having a constantly open inlet permitting reflux of some of the fluid in response to the pressure transmitted from said reciprocating piston.

8. A pump comprising two pumping elements one of which is movable relative to the other to force fluid through the pump, one of said pumping elements having a passageway for the fluid and a valve seat in said passageway, and a valve secured to the other pumping element and adapted to engage said valve seat.

9. A pump comprising two pumping elements one of which is movable relative to the other to force fluid through the pump,

the other to force fluid through the pump, one of said pumping elements having a passageway for the fluid and a valve seat in said passageway, a valve secured to the other pumping element and adapted to engage said valve seat so as to limit the motion of the movable pumping element, and a spring cooperating with said movable pumping element to yieldingly retain said valve seat and valve in engagement with each other.

10. A pump comprising two pumping elements one of which is movable relative to the other to force fluid through the pump, one of said pumping elements having a passageway for the fluid and a valve seat in said passageway, a valve secured to the other pumping element and adapted to engage said valve seat and a spring cooperating with said movable pumping element to close said valve.

11. A pump comprising two pumping elements one of which is movable relative to the other so as to force fluid through the pump, and operating means comprising a striking member movable into and out of engagement with the movable pumping element, said striking member and movable pumping element having registering discharge passageways through which fluid is discharged while the striking member is engaged with the movable pumping element, the discharge passageway in said movable pumping element being provided with a valve seat, and a valve secured to the other pumping element and adapted to engage said valve seat so as to limit the motion of said movable pumping element.

12. A pump comprising a stationary pumping element, a movable pumping element cooperating with said stationary element to force fluid through the pump, said movable pumping element having a discharge passageway for the fluid and a valve seat in said discharge passageway, and a valve secured to the stationary pumping element and adapted to engage said valve seat.

13. A pump comprising a stationary pumping element, a movable pumping element cooperating with said stationary element to force fluid through the pump, said movable pumping element having a discharge passageway for the fluid and a valve seat in said discharge passageway, a valve secured to said stationary pumping element and adapted to engage said valve seat, and a spring cooperating with said movable pumping element to yieldingly force said valve seat into engagement with said valve.

14. A pump comprising a stationary pumping element, a movable pumping element telescoping therewith, said movable pumping element having a discharge passageway and a valve seat therein, a striking member adapted to engage said movable pumping element to impart movement thereto, a valve adjustably secured to said stationary pumping element and adapted to engage said valve seat so as to limit the motion of said movable pumping element, and a restoring spring cooperating with said movable pumping element to force said valve seat into engagement with said valve.

In testimony that I claim the foregoing I hereunto affix my signature.

REINHARD HILDEBRAND.
